UNITED STATES PATENT OFFICE

2,596,183

METHOD FOR INCREASING THE VOLUME OF SHREDDED TOBACCO

Frank J. Sowa, Cranford, N. J., assignor to American Machine and Foundry Company, a corporation of New Jersey

Application December 2, 1944, Serial No. 566,365

6 Claims. (Cl. 131—140)

1

This invention relates to preparing shredded tobacco for formation into cigarettes, and more particularly to a method of expanding and permanently increasing the size of each shred, of a quantity of cased or uncased tobacco, by treating or subjecting it to such treatment as will cause it to absorb substantial quantities of moisture, such as water, and thereby cause the tobacco so treated to have a greater filling power.

Filling power of shredded cigarette tobacco may be defined as the volume that a given weight of such tobacco occupies under a definite pressure, or in other words, the force exerted by a given weight of shredded cigarette tobacco in a given volume. An increase in filling power may, therefore, be termed the capacity of a smaller weight of shredded cigarette tobacco to occupy the same volume and exert the same expansive force as would a larger weight of untreated shredded cigarette tobacco.

I have discovered that the filling power of shredded cigarette tobacco can be increased and thus contribute to manufacturing economy by subjecting a given quantity or a batch of tobacco to substantial quantities of moisture in excess of the quantity normally present as moisture content in such tobacco upward to 125 per cent of the weight of the shredded cigarette tobacco treated. Best results have been obtained by treating such tobacco with between 50—125 per cent water by weight. This treatment causes the cells of tobacco being processed to swell, which therefore results in a permanent expansion of each particle or tobacco shred, such that the filling power or yield after the moisture content is reduced to normal, say 10—13 per cent, is greatly increased when compared with untreated samples, and at the same time the normal physical and chemical characteristics of the tobacco remain unchanged.

This reaction of shredded cigarette tobacco is especially valuable at present where the demands are great because it means that more satisfactory cigarettes and like smoking articles can be made from a limited supply of tobacco, while at the same time an adequate supply of such smoking articles can be maintained.

The increase in filling power of tobacco resulting from its subjection to absorption of substantial quantities of moisture as by spraying, dipping, exposure in a moist atmosphere for a period of time, or other suitable manner, means that cigarettes having the same amount of tobacco will produce a better filled plumper, firmer cigarette, one less likely to break in handling, and also make possible savings in tobacco.

2

It is an object of my invention, therefore, to provide an improved method of expanding tobacco, especially shredded cigarette tobacco.

It is a further object of my invention to expand a quantity or batch of shredded cigarette tobacco by applying thereto a liquid, such as water, in substantial quantities or in a quantity greater by weight than the amount of moisture normally present in tobacco being processed.

10 It is a further object of my invention to subject a quantity of shredded cigarette tobacco to moisture application to such an extent that the tobacco treated is enabled to absorb a substantially greater quantity of moisture than that normally present in tobacco about to be manufactured into cigarettes, whereby the excess moisture is responsible for an expansion of the cells and walls of each tobacco shred subjected to treatment in order to cause the resulting product 15 after the moisture content is reduced to normal, say 10—13 per cent, to have a greater filling power.

20 It is also an object of my invention to increase the physical size of shreds of cigarette tobacco by treating shredded tobacco with an excess of water over that normally present in the tobacco to be treated, say 10—13 per cent, and effect a concurrent deformation of shreds which results in an increased size of shred having a wavy appearance tending to resist crushing and flattening thereof.

25 Other objects of my invention will be set forth in the following description and drawings which illustrate preferred embodiments thereof, it being understood that the above statements of the objects of my invention are intended generally to explain the same without limiting it in any manner.

30 In the accompanying drawings which form a part of this specification, and in which like characters of reference indicate the same or like parts:

35 Figure 1 is a perspective view showing mechanism suitable for carrying out the process constituting the invention; and

40 Figure 2 is a view illustrating diagrammatically a modified method of performing the invention.

45 In carrying out the method of this invention, shredded cigarette tobacco may be subject to moisture application in any suitable manner. In usual cigarette manufacture, the curled and irregular cigarette tobacco leaf pieces are shredded into narrow crooked strands or shreds about one thirty-second to one fifty-second of an inch in width, which when cut may be as long as the 50 length or width of the leaf piece from which the

shreds are cut. Referring to the drawings, Figure 1 shows a preferred method in which a chute 10 feeds shredded tobacco S into a hopper 12 delivering to an inclined elongated revolving cylinder 14 of any suitable conventional type, turning on flanged rollers 18 mounted in brackets 20 fixed to cross bars 21 secured to side frames 22. Cylinder 14 may be provided with a ring gear 23 which meshes with a driving gear 24 mounted on a shaft (not shown) connected in any suitable manner with drive shaft 26 journalled in bearings 28 carried by side frames 22, and provided with a pulley 30 driven by belt 32 by a suitable source of power, such as a motor (not shown). Cylinder 14 is rotated at any desirable speed suitable for uniform moisture application.

As indicated in Figure 1, the interior of the cylinder 14 is furnished with a plurality of baffle plates 34, preferably spirally arranged, and extending longitudinally within cylinder 14, which engage the tobacco passing through the cylinder 14, and tumble it around in order that liquid, such as water, may come into intimate contact with the tobacco being treated as it passes through the cylinder 14 from hopper 12 onto conveyor 36. In the illustrated embodiment, there are provided a plurality of spraying nozzles 38, preferably designed to apply moisture as a spray or mist, fixed to a pipe 40 provided with valves 42 by means of which the supply of water to the nozzles may be controlled. Nozzles 38 may be of any suitable conventional type adjustable to control the kind of spray; that is, from a heavy spray to a mist. A tank 44 fed from a source of supply by a pipe 46 and supported by straps 48 above the cylinder 14 insures an adequate quantity of water at all times.

The amount of shredded tobacco passing from hopper 12 into cylinder 14 preferably is determined before it enters the cylinder. In a similar way the quantity of water to be applied thereto may be measured into tank 44 so that the proper percentage of water can be applied to a given batch of tobacco undergoing treatment. For example, if a batch of one hundred pounds of shredded cigarette tobacco is being treated, and a twenty-five per cent water treatment is to be given, then twenty-five pounds of water will be sprayed through nozzles 38 upon the tobacco being passed through cylinder 14. The speed of rotation of cylinder 14 and setting of nozzles 38 determines the time of application of moisture to the batch of tobacco being processed. Other percentages of water can be applied as desired. Tests actually show that applications of moisture from 25 per cent up to 125 per cent by weight resulted in permanent increase in size of shred of tobacco treated although the most substantial increases occurred when quantities of moisture range between 50 and 125 per cent by weight. The results of tests are tabulated hereinbelow.

Shredded cigarette tobacco treated with substantial quantities of moisture is discharged from cylinder 14 onto conveyor 36 is traveled beneath rotating star wheels 50 fixed to shaft 52 mounted for rotation in side frames 53, and provided with a pulley 54 on which runs a belt 56 driven by a motor or other suitable source of power (not shown).

Conveyor 36 runs upon pulleys 58, 60. Pulley 58 is mounted on a shaft 62 mounted for rotation in side brackets 53. Pulley 60 is mounted on a shaft 66 supported by brackets 68 secured to the exterior of drier D (Figure 1). Shaft 62 is provided with a sprocket 70 on which travels a

sprocket chain 72 running on a sprocket 74 on shaft 66. Conveyor 36 is driven by means of a sprocket 76 secured to shaft 62 by means of a sprocket chain 78 running on a sprocket (not shown) fixed to shaft 26. In this manner conveyor 36 is driven in proper timed relation at any suitable speed requisite for proper drying of the tobacco to convey the spread-out wetted tobacco to and through a drier D which may be of any well-known conventional design. Drier D is provided with vents 80 which allow moisture to escape therefrom. Tobacco issuing from the drier contains approximately 10-13 per cent moisture, preferably approximately 12 per cent. The moisture content of shredded tobacco about to be manufactured into cigarettes is generally so controlled according to temperature and relative humidity within the factory that the desired moisture content of between 10-13 per cent, preferably approximately 12 per cent, is maintained substantially constant. For example, the desired moisture content may be maintained with a room temperature of 70° F. and relative humidity of about 57 per cent. Obviously other temperatures and relative humidity variations can be made according to climatic or manufacturing conditions.

As indicated in Figure 1, conveyor 36 may be made of a foraminous material such as wire mesh which allows ready circulation of heat within the drier D through the tobacco spread out thereon.

The effect of the water upon each shred of tobacco is such that the cell walls expand permanently and give greater volume or filling power thereto. Microscopic examination of samples of specimens treated demonstrate this increase. For example, average of three tests shows:

Sample No.	Per Cent H ₂ O	Shred width	Per Cent increase in shred width
0.....	0	5.5	
1.....	75	8.5	59.1 increase over 0 sample.
2.....	125	9.1	65.4 increase over 0 sample.

The increase in the size, especially the width (thickness) of the individual shreds apparently is caused by the swelling of the side walls or the mesophyll, as well as the interior cells of the leaf or shred when wet with water. The removal of water, however, does not result in a shrinkage or return of shred to the condition prior to water application and treatment. In other words I have found that because of this treatment, treated tobacco is always of increased size relative to a comparative untreated sample, and therefore, has greater filling power.

According to the modified method shown in Figure 2, the shredded cigarette tobacco is processed in substantially the same manner as in Figure 1. That is, the shredded tobacco is subjected to moisture absorption beyond that normally present in tobacco at usual temperatures and relative humidity, as indicated at 1 with any desired amount of water, substantially greater in weight than the weight of water normally present in the shredded tobacco to be treated. The amount of water applied may range upward from 25 per cent to say 125 per cent of water by weight depending upon the results desired by the processor, although best results are obtained with quantities of moisture ranging from 50-125 per cent by weight. Following the moisture applying operation, the tobacco is dried as at 2 in the same type of drier D as indicated in Figure 1. However, as distinguished from

drying in Figure 1, the moisture is reduced to substantially 5 per cent or less after which the tobacco is placed in a rehumidifier 3 of conventional design in which the moisture content is raised to a fixed amount, say 10-13, preferably approximately 12 per cent, when it is ready for manufacture into cigarettes.

In order to show conclusively the increase in volume of the tobacco treated in the manner described, several batches of tobacco were processed. Samples were taken from each batch treated and dried until approximately 5 per cent moisture remained therein. By drying to a fixed amount of moisture content, it is considered that a closer control of the final moisture content for testing purposes can be effected than if attempts are made to dry rapidly to, say 10-13 per cent moisture content, and then make a comparison.

The above referred to samples were tested somewhat as follows: A weighed quantity of 8.500 grams of treated, shredded cigarette tobacco was placed in a cylindrical glass container of uniform diameter and a weighted metal disk having a diameter slightly less than that of the cylinder was placed in the cylinder on top of the sample. The disk was attached to an indicator which traveled over a scale reading in millimeters. Readings on the scale represented the drop in millimeters of the weighted disk. By calibrating the instrument it was possible to determine the height of the tobacco in the cylindrical container during compression. The height was directly proportional to the volume. Therefore, by measuring the height of tobacco in the cylindrical container during compression and comparing the scale reading with a calibrating table it gave the height of the tobacco from which the compressed volume was computed. The scale indicator would move more rapidly at first, and then slow down to a point where no appreciable movement was noted. Readings were taken at this point. The results of the series of tests are shown in the accompanying table.

Test A	Original volume in milliliters humidified to 10-13% moisture content	Weight of tobacco sample (grams)	Water added, per cent by weight of humidified tobacco	Volume after drying to 5% and humidifying 70 hours to increase moisture content to 10-13%	Per cent volume increase in comparison with original volume before treatment
No. 1..	66.4	8.500	0	69.2	
No. 2..	68.4	8.500	25	72.4	4.2
No. 3..	67.2	8.500	50	74.3	5.9

No. 5..	67.2	8.500	100	73.2	13.5
No. 6..	68.8	8.500	125	73.9	8.9
					7.5

Test B	Original volume in milliliters humidified to 10-13% moisture content	Weight of tobacco sample (grams)	Water added, per cent by weight of humidified tobacco	Volume after drying to 5% and then rehumidifying 2 months to 10-13%	Per cent volume increase in comparison with original volume before treatment
No. 1..	66.4	8.500	0	70.0	5.4
No. 2..	68.4	8.500	25	79.2	
No. 3..	67.2	8.500	50	80.4	17.9
No. 4..	68.0	8.500	75	85.4	18.2
No. 5..	67.2	8.500	100	85.4	27.2
No. 6..	68.8	8.500	125	85.4	24.2

In the table, test A was made from samples dried for a period of time sufficient to reduce the moisture content to approximately 5 per cent, after which the samples were humidified for seventy hours. It was considered that this treatment would result in a more uniform distribution of moisture throughout each sample tested. In test

B, the samples were dried to establish a moisture content of approximately 5 per cent after which they were rehumidified for two months to re-establish the moisture content to 10-13 per cent.

Following each test the volume of each sample was redetermined. A study of the per cent volumetric increase of the two series of tests as tabulated above, indicates that in substantially all cases an appreciable increase in volume resulted. Despite the fact that all samples were subjected to drastic treatment the tobacco volume was increased permanently.

The invention above described may be varied in construction within the scope of the claims, for the particular device, selected to illustrate the invention, is but one of many possible concrete embodiments of the same. It is not, therefore, to be restricted to the precise details of the structure shown and described.

20 What is claimed is:

1. The method of expanding tobacco in shredded form which comprises the steps of providing shredded tobacco having a moisture content of 10-13%, adding thereto only a quantity of water 25 having a weight not less than the total weight of said shredded tobacco, permitting said additional water to remain with said tobacco until said tobacco has substantially completely absorbed said water, reducing the moisture content of said tobacco to approximately 5%, and then increasing the moisture content of said tobacco to substantially its original content.

2. The method of expanding tobacco in shredded form which comprises the steps of providing shredded tobacco having a moisture content of 10-13%, adding thereto only a quantity of water 30 having a weight not less than 50% of the total weight of said shredded tobacco, permitting said additional water to remain with said tobacco until said tobacco has substantially completely absorbed said water, reducing the moisture content of said tobacco to approximately 5%, and

40

content of said tobacco to approximately 5%, and
